UNITED STATES PATENT OFFICE.

JAMES T. SHERIDAN, OF NEWARK, NEW JERSEY, ASSIGNOR TO THE CITY
BUTTON WORKS, OF NEW YORK, N. Y.

BUTTON-MAKING MACHINE.

SPECIFICATION forming part of Letters Patent No. 371,379, dated October 11, 1887.

Application filed June 16, 1887. Serial No. 241,496. (No model.)

To all whom it may concern:

Be it known that I, JAMES T. SHERIDAN, a citizen of the United States, residing at Newark, in the county of Essex and State of New Jersey, have invented new and useful Improvements in Button-Machines, of which the following is a specification.

This invention consists in a button-machine adapted for use in salesrooms and the like, and has for its object to provide a device which is more durable and can be more conveniently manipulated than those in use at the present time.

The novel features of construction whereby this object is accomplished are more fully pointed out in the following specification and claims, and illustrated in the accompanying drawings, in which—

Figure 1 represents a plan or top view of a button-machine containing my invention. Fig. 2 is a side elevation thereof. Fig. 3 is a vertical section in the plane xx , Fig. 1. Figs. 4, 5, and 6 are sectional elevations of detail parts. Fig. 7 shows the various parts composing a button.

Similar letters indicate corresponding parts.

In the drawings, Figs. 1, 2, and 3, the letter A designates the base of the machine, on the right-hand end of which is formed a suitable socket for the reception of a wooden block, which serves as a support, a, for the cloth to be cut in forming the cover b, Fig. 7, for the button. In a suitable frame, B, are formed bearings for the shank of a vertical chuck, C, to which is secured the cutter D in the usual manner. The cutter D is in the form of a tube provided with a sharp cutting-edge. The chuck is reciprocated by means of a hand-lever, E, that is pivoted to lugs on the frame B and to the chuck C at e.

In the base A is secured a vertical non-rotating spindle, F, Figs. 1, 2, and 3, about which can rotate a die-carrier, G, that is prevented from moving vertically by means of a screw-and-slot connection with the spindle F, or by other suitable means. On said carrier G are mounted a number of dies, each of which is adapted for a particular size of button, so that different sizes of buttons can be produced on the machine. In the example shown in the

drawings I make use of three such dies; but a greater number can be used, if desired. The dies each consist of a post, h, which is secured to the base A, or is formed integral therewith, and a sleeve, h', fitted to said post. In the sleeve h' is formed a slot, i, Fig. 2, having a longitudinal and a transverse branch, and through said slot extends a pin or screw, i', which is secured in the post, so that by turning the sleeve so as to bring the pin within the longitudinal branch of the slot i the sleeve h' can be lowered from the position shown in Fig. 4 to that shown in Fig. 6, or vice versa. The upper end of the sleeve h' is bored out to form a socket, i², for the reception of the cover b of the button, Figs. 1, 3, 4, and 7.

The punch J is cylindrical in form and can slide in a suitable guide-sleeve, J', said punch being held within the latter by means of a screw, h², which engages with a longitudinal slot therein. A suitable stop or shoulder, j³, limits the movement of the punch within the sleeve. One end of the punch is provided with a socket, j, for the reception of the shank b' of the shell, Figs. 4 and 5, and the other end of the same is provided with a shank-spreader, j', to open the shank b' after the collet b³, Fig. 7, has been properly placed, Fig. 6.

The punches are actuated by means of a hand-lever, K, Figs. 1 and 2, which is pivoted at k to the upper end of the spindle F, and is provided with two cams, k' k', on opposite sides thereof. The cams are so placed in order that they will not come into contact with and injure the shank-spreader j', Figs. 2 and 4. The guide-sleeve J' is provided with a contracted portion at each end, which fits the socket in the sleeve h', and a flange at each end abuts against the upper edge of said sleeve h'. These contracted portions guide the guide-sleeve to its proper position when removed for inserting the parts of the button. In one end of the guide-sleeve is a recess, j², having inclined walls, which recess receives the collet b³. To bring either of the punches directly under the cams of the hand-lever K a stop is provided, Fig. 2, which can consist of a pin, l, extending vertically through the base A, that is adapted to engage with a recess in the bottom of the die-carrier G. A spring, l', 100

bearing against a head on the pin, forces the same into the recess when the same is brought in line with said pin.

In the operation of the machine the die for 5 the particular size of button is brought into its proper position under the hand-lever K. The cover b is cut by means of the cutter D and placed within the socket i² of the guide-sleeve J', Fig. 4. The shell and its shank b', which 10 have been previously united in the usual way, are then inserted into the proper end of the punch J, the said shank b' entering the socket j, Fig. 4. The guide-sleeve J' and its contained punch and shell are placed over the 15 die, Figs. 2 and 4, and the hand-lever is depressed to the position shown in Fig. 5, thereby by turning the edge of the cover b upward about the shell, Fig. 5. The guide-sleeve J' and the contained punch are then removed, 20 leaving the cover and shell in the die in the position shown in Fig. 5. The collet b² is now inserted in the recess j² and the guide-sleeve and punch are replaced on the die, Fig. 6, in a position inverse to their prior position, Fig. 25 4. The sleeve h' of the die is now turned and lowered to the position shown in Fig. 6, and the hand-lever is depressed, thereby forcing the collet on the cloth cover, the edges of which are turned inward and beneath the col- 30 let. At the same time the shank-spreader turns the upper edge of the shank down upon the collet, thereby firmly securing the collet to the button. The lowering of the die-sleeve h' allows the edge of the cover to be turned 35 inward by the collet, which would not be the case if the turned-up portion of the cover were against the walls of the sleeve h', as in Fig. 5. For each size of button a separate punch and guide-sleeve and cutter are employed.

40 What I claim as new, and desire to secure by Letters Patent, is—

1. In a button-machine, the combination, with a die, of a reversible punch having one of its ends provided with a recess for the reception of the button-shank, and its other end provided with a shank-spreader and adapted to receive the collet, substantially as shown and described. 45

2. The combination, with the guide-sleeve, of a punch having one of its ends provided with a recess for the reception of the button-shank, and its other end provided with a shank-spreader, substantially as shown and described. 50

3. The combination, with the guide-sleeve 55 having a recess, j², of a punch guided longitudinally in the same, stops for the punch, said punch being provided with a recess on one end for the reception of the button-shank, and on its other end with a shank-spreader, 60 substantially as shown and described.

4. A die consisting of the stationary post h, the sleeve h', arranged on the post, and a pin-and-slot connection between the post and sleeve for adjusting the latter upward and 65 locking it in such position, substantially as described.

5. In a button-machine, the vertically-reciprocating cutter D, in combination with the rotary carrier G, the dies h h' on the same, 70 punch J, the guide-sleeve J' for the same, provided with a recess, j², said punch being provided on one end with a recess, and on its other end with a shank-spreader, substantially as shown and described. 75

In testimony whereof I have hereunto set my hand and seal in the presence of two subscribing witnesses.

JAMES T. SHERIDAN. [L.S.]
